CONTINUOUS HEATING FURNACE

William A. Morton, Mount Lebanon Township,
Allegheny County, Pa., assignor to The Amsler-
Morton Company, Pittsburgh, Pa., a corpora-
tion of Pennsylvania

Application May 31, 1940, Serial No. 337,988

15 Claims. (Cl. 263—40)

This invention relates generally to heating furnaces and more particularly to heating furnaces of the type wherein articles are heated as they are continuously moved therethrough.

In the steel industry a continuous type heating furnace is employed for uniformly heating billets, ingots, blooms, slabs, rails and the like, to a predetermined temperature, preparatory to rolling or performing other operations thereon.

This type of furnace ordinarily contains two chambers, namely, a preheating chamber and a main heating chamber. The latter chamber is ordinarily provided with a soaking hearth adjacent the discharge end thereof. The preheating chamber is omitted when the furnace is to be used for certain types of heating.

The material to be heated continuously passes through these chambers in the order named and each article, when discharged from the furnace, is uniformly heated to the proper temperature for the operation that is to be performed thereon.

There are several different kinds of hearth structures employed in the continuous type of heating furnace art. The most common type of hearth is a flat refractory surface over which the steel is moved as it passes through the furnace. The firing is wholly above the steel and the furnace is used principally for the heating of thin slabs, such for instance as slabs four inches thick.

Another type of hearth structure supports the steel on water cooled skids, permitting the application of heat both above and below the steel. The skids form horizontal beams and are supported upon spaced piers or refractory pillows. In some instances the flame is directed from a common level toward the hearth and against the steel which acts as a division wall, causing the flame to split, one portion of the flame passing above and the other below the steel. There was no definite control of the quantity of fuel passing above or below the steel and poor heating of the steel resulted. The heating medium travels in the same direction as the movement of the steel. This type of furnace is fired from the discharge end and the steel becomes overheated when the rate of production is changed. Again one of the two chambers, above or below the steel, is always favored, which results in non-uniform heat distribution, in the vertical plane.

To avoid these difficulties independent burners have been placed above and below the steel to insure proper heat distribution. This method of firing has been practiced in two ways, first by placing the burners at the charging end of the furnace with the waste gases removed at the dis-

charge end, and second, by placing the burners at both the charging and discharge ends with the waste gases removed at the center of the furnace. With this character of hearth structure it is impossible to control the furnace atmosphere and it is difficult to control the firing because the firing chambers above and below the steel are connected with one another around the ends of the steel articles.

Another character of hearth structure permits the flame to travel above the steel in the same direction of its movement and the waste gases at the discharge end are then circulated back under the steel and pass out through flues adjacent the firing end. This method is impractical because the flame, which is above the steel, loses a greater portion of its heat before it is drawn down under the steel, and the gases which are extensively cooled vary greatly in temperature and the top and bottom of the steel is not uniformly heated.

The principal object of this invention is the provision of a continuous type heating furnace having independent firing chambers above and below the steel to be heated.

Another object is the provision of a continuous type heating furnace having independent firing chambers separated by the steel being heated and wherein the flame propagation in both chambers is in the same direction.

Another object is the provision of independent firing chambers in a heating furnace which are separated by the steel being heated and which are fired separately but exhausted into a common flue.

Another object is the provision of a continuous heating furnace having a preheating chamber and a main heating chamber and a hearth extending therethrough for supporting the steel to be heated which divides the preheating and the main heating chambers in the plane of the hearth into an upper and lower independent firing chamber.

Another object is the provision of an irregularity in the surface of the soaking hearth for causing each successive article to directly expose its sides to the application of heat when moved thereover.

Other objects and advantages appear in the following description and claims.

The accompanying drawings disclose a practical embodiment illustrating the principles of this invention wherein:

Fig. 1 is a sectional view taken longitudinally of a continuous type furnace comprising this invention.

Fig. 2 is a horizontal sectional view taken along the plane of the hearth of the furnace shown in Fig. 1.

Fig. 3 is a vertical sectional view taken along the line 3—3 of Fig. 1.

Fig. 4 is a sectional view taken longitudinally of another style continuous type furnace employing this invention.

Referring to Fig. 1, the furnace illustrated therein is made up of two sections, the heating chamber 10 having an extended soaking hearth 11, and a preheating chamber 12. The preheating chamber 12 is omitted when the furnace is employed for heating certain kinds of steel. Water cooled skids 13, which form the hearth for supporting the steel, extend through the preheating chamber 12 and the main heating chamber 10 to one end of the solid soaking hearth 11 and from the other end of the soaking hearth to the discharge end of the furnace. The material 14 to be heated is charged through the opening 15 into the preheating chamber 12 and is moved through the furnace along the skids and the soaking hearth, from whence it is discharged through the opening 16. When not in use the openings 15 and 16 are closed by suitable doors.

The main heating chamber and the preheating chamber are divided by the steel charge 14 into upper and lower independent firing chambers 17 and 18. The chamber 17, which is above the steel, is enclosed by the roof 19 and the side walls 20. The steel charge 14 forms the bottom of this chamber. The chamber 18 is formed by the steel 14 and the floor 21, which is below the plane of the hearth, and the continuous vertical walls 22 which rise from the floor 21 and support the outermost skids 13 as shown in Figs. 2 and 3. The walls 22 are closely adjacent the side walls 20 of the furnace and extend from the end wall 23 of the preheating chamber to the intermediate transverse furnace wall 24 at the end of the soaking hearth. Thus the lower heating chamber 18 is roofed in by the materials being heated. The intermediate skids 13 are supported on the short continuous walls 25 in the preheating chamber and on the piers 26 within the main heating chamber 10.

The rear wall 26' of the furnace is provided with two rows of burners 27 and 28 for firing the chambers 17 and 18 respectively. These burners are supplied with fuel carried by the conduits 30 and with preheated air carried by the ducts 31 and 32 respectively. As shown in Figs. 2 and 3, three burners 28 are arranged to fire the chamber 18 between the vertical walls 22, while the space outside of the walls 22 or between the walls 22 and each of the side furnace walls 20 is fired with the burners 29. The flame from the latter burners heat the under side of the ends of the articles and a portion of the products of combustion from these flames may travel up around the ends of the steel articles into the chamber 17.

The soaking hearth 11 may be heated by flames issuing from the rows of burners 33 in the front wall 34 of the furnace. These burners may be supplied with preheated air if desired.

The preheating chamber 12 is fired directly by the upper and lower rows of burners 35 and 36. The outer burners 37 in the lower row heat the spaces between the walls 22 and the side walls 20 of the heating chamber which correspond to the same portions heated by the burners 29 in the main heating chamber of the furnace.

The burners of the preheating chamber are ordinarily of less capacity than those of the main heating chamber and may be supplied with preheated air by a branch line from the conduit 31.

5 The air induced by the pressure of fuel in these burners and the slight infiltration of air through the charging opening is utilized in supporting the combustion of the fuel. Combustion is substantially complete before the gases reach the main 10 chamber 10 and these burnt gases thereafter blanket the steel as they travel to the exhaust flues at the discharge end of the furnace. In this manner the atmosphere surrounding the steel may be controlled to prevent excess oxidation and/or decarburization of the steel. Radiant heat energy from the hottest part of the flames issuing from the main burners 27 and 28 is thus prevented from being applied directly on the steel.

20 The preheated steel is thus subjected to radiant heat energy from the furnace surfaces and the flames in both the upper and lower heating chambers 17 and 18 which must pass through the products of combustion blanketing the steel. If the steel is subjected to the direct radiation of the flames, which is the present practice, the steel is heated in streaks. Streak heating is detrimental in rolling and other mill operations. This disadvantage is overcome by diffusing the 30 radiant heat energy as it passes through the blanketing layer of the products of combustion from the preheating chamber. When the combustion of the main burner flames is substantially complete the products of combustion from both 35 the preheating flames and the main burner flames combine and continue to blanket the steel as they pass on through the furnace. In this manner the atmosphere adjacent the steel is controlled and prevents excess oxidation and decarburization of the steel.

40 The radiant heat energy being diffused as it passes through the blanketing products of combustion, thereby provides a uniform temperature throughout each article of steel, which eliminates the detrimental effects due to direct heating from initial flame combustion. Again the efficiency of the heat exchange is increased by the extended flame length and the location of the hottest heating areas may be accurately determined.

45 The hot waste gases passing from the chamber 18 and from the side burners 29 and 37 below the plane of the hearth, as shown in Fig. 2, flow up over the transverse wall 38 and down through the flues 40 which are connected at their lower ends with the transverse flue 41.

50 The hot waste gases passing from the chamber 17 above the plane of the hearth continue to blanket the steel, as it passes over the soaking hearth 11, and are drawn down past the discharge opening 16 into the flues 42 which are connected at their lower end to the transverse flue 43. This prevents the entrance of cold air into the furnace chamber, as any infiltration of air through the discharge door is drawn down directly into the flues.

55 The flames produced by the burners 33 travel rearwardly over the soaking hearth 11 substantially parallel with the steel until the velocity of the burning gases is reduced to such an extent that the draft induced by the flues 40, in the vicinity of the burners 33, reverses the path of movement of the products of combustion. Combustion is substantially complete before the gases are redirected and mingle with the gases blanketing the steel. Thus the flames in the

discharge end of the furnace heat the steel by radiant heat energy in a manner similar to that described above and the hottest portion of these flames is along their initial path. Thus the steel is protected by the products of combustion during the most critical periods of the heating process.

The collecting flues 41 and 43 are connected by the flue 44 to the recuperator 45. The waste heat gases then pass through the recuperator to the main flue 46 and thence to the stack.

The flues 40 and 42 are controlled by the dampers 47 which are operated by the servomotors 48.

The burners 33 heating the steel on the soaking hearth may be operated at the same time as the main burners 27, 28. However under normal operating conditions the burners 33 are preferably required to function only during mill delays when the main burners are shut down. During mill delays the movement of the steel through the furnace is stopped and the furnace temperature rises. The automatic controls then operate to reduce the firing rate of the main burners until this rate is reduced to a predetermined quantity at which time an automatic transfer is effected for shutting down the main burners and firing the burners 33. These burners are then automatically regulated by the same control mechanism to maintain the steel on the soaking hearth at its proper rolling temperature. When the steel is again taken from the soaking hearth for rolling and new steel is supplied to the charging end the automatic controls are again actuated by the temperature of the furnace to transfer the firing back to the main burners for normal operating conditions.

The temperature of the furnace is controlled automatically by a fluid system actuated by the pyrometer 49 which measures the temperature of the waste gases passing out of the furnace and down through the flue 42, for the purpose of control. The temperature of these gases have a direct relation to the temperature of the steel which they blanket. This temperature controller regulates the quantity of air delivered by the blower 50 to the recuperator and the fuel delivered to the burners is in turn fed in proportionate quantities with respect to the quantity of air supplied. The pressure of the furnace is automatically regulated by the damper 51 in the flue 46. This damper is controlled by the motor 52 actuated by a mechanism which receives pressure impulses from the furnace. These impulses are preferably taken from the soaking chamber.

The soaking hearth 11 may be provided with some means for vertically shifting the individual articles during their travel over the soaking hearth. Such a movement exposes the sides of the articles permitting them to receive the same heat treatment as the normally exposed surfaces. Thus the body and the surfaces of the articles are heated uniformly and provide improved material for rolling or other operations.

The articles may be vertically shifted by a mechanically operated device, manually, or by providing elevations or depressions in the surface of the soaking hearth. The latter provides the simplest form for articles which are substantially square or rectangular in cross section. It may be found preferable to vertically shift the whole of the article at one time as some articles may deviate sideways due to their particular shape if one end is raised or lowered.

In Figs. 1 and 2 a transverse depression 53 and a hump or elevation 54 is shown in the sur-

face of the soaking hearth 11 adjacent the discharge end. As the steel articles are moved over this portion of the hearth the sides become exposed to products of combustion. These surface formations may be constructed to roll each article completely over or throw it on its side. Again a plurality of these transverse surfaces may be provided along the soaking hearth and properly spaced from one another to shift several articles so that their sides are exposed just at the time the leading article is discharged from the furnace.

In the furnace structure shown in Fig. 4, the burners 27 and 28, which fire the upper and lower independent heating chambers 17 and 18 respectively, are faced in the opposite direction to that shown in Fig. 1. The preheating chamber 12 is not provided with burners and the products of combustion from both of the chambers 17 and 18 flow through the upper and lower levels of the preheating chamber 12, down through the vertical flues 40, past the charging door 15, and along the horizontal flue 44 to the recuperator and out the flue 46 to the stack. The flames from the burners 33 project into the furnace chamber over the soaking hearth 11 until the velocity of the gases is reduced sufficiently to redirect them back over the steel, in the same manner as that described above. These gases are then discharged through the flues 42 and the damper controlled auxiliary stack 55.

In each of the structures illustrated in Figs. 1 and 4 the two firing chambers, above and below the steel, extend from the preheating chamber 35 through the main heating chamber. These chambers are structurally independent from one another except for the common partition formed by the steel being heated as illustrated. These firing chambers may be exhausted to the same or separate flues. However this does not affect the efficient operation of each of these firing chambers.

Ordinarily the furnace is constructed so that the ends of the steel articles are supported on the outer hearth skids 13. However this furnace can be successfully operated by placing two shorter articles of steel in longitudinal alignment with their adjacent ends touching. Only four hearth skids are shown in Fig. 2 but more may be added if shorter lengths of steel are to be heated. If this is done it may be necessary to relocate the main burners 28 and 29 and the preheating burners 36 and 37 so that the flames will not play directly on the piers.

55 I claim:

1. A continuous furnace for heating billets and the like comprising upper and lower interior portions which during the operation of the furnace are separated into distinct and non-communicating chambers by the row of billets passing through the furnace on spaced apart skids supported by continuous solid walls, and independently controlled separate means for introducing heating flames into and withdrawing the products of combustion from each of said chambers to heat the billets from above and below.

2. A continuous furnace for heating billets and the like comprising upper and lower interior portions which during the operation of the furnace are separated into distinct and non-communicating chambers by the row of billets passing through the furnace on spaced apart skids supported by continuous solid walls, and independently controlled separate means for introducing heating flames into and causing them to travel

in the same direction in both chambers for substantially the full length thereof longitudinally of the furnace to heat the billets from above and below.

3. A continuous furnace for heating billets and the like comprising upper and lower interior portions which during the operation of the furnace are separated into distinct and non-communicating chambers by the row of billets passing through the furnace, and separate means for introducing heating flames into both chambers and causing them to travel in the direction of the travel of the billets for substantially the full length of said chambers.

4. A continuous furnace for heating billets and the like comprising a preheating portion and a heating portion connected thereto and through which the billets pass in turn, the upper and lower interiors of said portions being divided by the row of billets being heated which slide on spaced apart skids supported by continuous solid walls to form separate and non-communicating chambers longitudinal of the furnace above and below the row of billets, and independently controlled means for the separate introduction of heating flames into each of said chambers.

5. A continuous furnace for heating billets and the like comprising a preheating portion and a heating portion connected thereto and through which the billets pass in turn, the upper and lower interiors of said portions being divided by the row of billets being heated which slide on spaced apart skids supported by continuous solid walls to form separate and non-communicating chambers longitudinal of the furnace above and below the row of billets, and independently controlled separate means for introducing heating flames into and causing them to travel in the same direction in both chambers longitudinally of the furnace to heat the billets from above and below for substantially the full length of said chambers.

6. A continuous furnace for heating billets and the like comprising a preheating portion and a heating portion connected thereto and through which the billets pass in turn, the upper and lower interiors of said portions being divided by the row of billets being heated which slide on spaced apart skids supported by continuous solid walls to form separate and non-communicating chambers longitudinal of the furnace above and below the row of billets, and separate means for introducing heating flames into both chambers and causing them to travel in the direction of the travel of the billets for substantially the full length of said chambers.

7. In a continuous furnace for heating billets and the like having side walls and roof, a pair of longitudinally disposed continuous inner walls within the furnace and spaced from the side walls, skids carried by the tops of said inner walls, the billets traveling along said skids in their passage through the furnace forming a continuous partition completing a chamber beneath the billets and between the inner walls and forming non-communicating independent upper and lower chambers, and means for independently introducing and controlling heating flames into the interior of the furnace above the billets and into the chamber beneath the billets.

8. A continuous furnace for heating billets and the like, comprising a preheating portion and a heating portion through which the billets pass in turn, a pair of continuous inner walls longitudinal of the interior of the furnace and spaced

from each other and from the side walls of the furnace and along the tops of which inner walls the billets move forming a continuous partition completing a chamber beneath the billets and between the inner walls and which extends through the preheating and heating portions of the furnace, said walls and billets forming non-communicating independent upper and lower preheating and heating chambers, and means for independently introducing and controlling heating flames into the furnace above and below the billets.

9. A continuous furnace for heating billets and the like comprising upper and lower interior portions which during the operation of the furnace are separated into two distinct and non-communicating chambers by the row of billets passing through the furnace on spaced apart skids supported by continuous solid walls, and independently controlled separate means for introducing heating flames into both chambers and causing the same to travel in the direction opposite to that of the travel of the billets for substantially the full length of said chambers.

10. A continuous furnace for heating billets and the like, comprising a preheating portion and a heating portion through which the billets pass in turn, a pair of continuous inner walls longitudinal of the interior of the furnace and spaced from each other and from the side walls of the furnace and along the tops of which inner walls the billets move forming a continuous partition completing a chamber beneath the billets and between the inner walls and which extends through the preheating and heating portions of the furnace, said walls and billets forming non-communicating independent upper and lower preheating and heating chambers, and independently controlled means for the separate introduction of heating flames into the furnace above and below the billets and causing the same to travel in the direction opposite to that of the travel of the billets for substantially the full length of said chambers.

11. A continuous furnace for heating billets and the like comprising a heating portion which when the furnace is in operation is divided by the row of billets passing through the furnace on spaced apart skids supported by continuous solid walls into independent and non-communicating upper and lower heating chambers, a soaking hearth adjacent the discharge end of the furnace over which the billets pass, independently controlled means for introducing heating flames into each of said heating chambers and causing them to travel in the direction opposite to that of the travel of the billets for substantially the full length of said chambers, means for introducing heating flames adjacent the discharge end of the furnace, and means for redirecting the products of combustion from said flames toward the discharge end of the furnace and between the flames and the billets.

12. A continuous furnace for heating billets and the like comprising upper and lower interior portions which during the operation of the furnace are separated into distinct and non-communicating chambers by the row of billets passing through the furnace, separate means for introducing heating flames into both chambers and causing them to travel in the direction of the travel of the billets for substantially the full length of said chambers, and separate means for discharging the products of combustion from each chamber.

13. A continuous furnace for heating billets and the like comprising upper and lower interior portions which during the operation of the furnace are separated into distinct and non-communicating chambers by the row of billets passing through the furnace, separate means for introducing heating flames into both chambers and causing them to travel in the direction of the travel of the billets for substantially the full length of said chambers, separate means for discharging the products of combustion from each chamber, and means for controlling the rate of withdrawal of the products of combustion through said discharge means.

14. A continuous furnace for heating billets and the like, comprising a preheating portion and a heating portion through which the billets pass in turn, a pair of continuous inner walls longitudinal of the interior of the furnace and spaced from each other and from the side walls of the furnace and along the tops of which inner walls the billets move forming a continuous partition completing a chamber beneath the billets and between the inner walls and which extends through the preheating and heating portions of the furnace, said walls and billets forming non-communicating independent upper and lower preheating and heating chambers, means for introducing heating flames into the furnace above and below the billets, separate means for discharging the products of combustion from each chamber, and means for controlling the rate of withdrawal of the products of combustion through said discharge means.

and heating chambers, independently controlled means for introducing heating flames into the furnace above and below the billets, and separate means for discharging the products of combustion from each chamber.

15. A continuous furnace for heating billets and the like, comprising a preheating portion and a heating portion through which the billets pass in turn, a pair of continuous inner walls longitudinal of the interior of the furnace and spaced from each other and from the side walls of the furnace and along the tops of which inner walls the billets move forming a continuous partition completing a chamber beneath the billets and between the inner walls and which extends through the preheating and heating portions of the furnace, said walls and billets forming non-communicating independent upper and lower preheating and heating chambers, means for introducing heating flames into the furnace above and below the billets, separate means for discharging the products of combustion from each chamber, and means for controlling the rate of withdrawal of the products of combustion through said discharge means.

WILLIAM A. MORTON.
